POLARIZED OUTLET AND PLUG

Walter W. Davis, Campton, N.H.

Application October 22, 1957, Serial No. 691,711

3 Claims. (Cl. 339—182)

This invention relates to electrical connector devices, and more particularly to a polarized receptacle and plug arrangement for use in conjunction with domestic power systems of the type having a grounded conductor.

A main object of the invention is to provide a novel and improved polarized receptacle and plug for use therewith, the receptacle and plug being especially suitable for use in conjunction with conventional electric wiring including a grounded conductor, the receptacle and plug being simple in construction, being easy to install, and providing a means whereby appliances of the polarized type may be properly connected to the line conductors for energizing same.

A further object of the invention is to provide an improved polarized plug and receptacle for use therewith, the plug and receptacle being inexpensive to manufacture, being durable in construction, being arranged so that correct polarity is positively maintained, the receptacle being neat in appearance, and the plug and receptacle being easily connected together.

A still further object of the invention is to provide an improved plug receptacle of the polarized type especially suitable for use in conjunction with domestic wiring systems, the receptacle being compact in size, being arranged to firmly hold a plug inserted therein, and being provided with spacing between the contacts thereof of sufficient magnitude to insure that no short circuits will occur in the receptacle.

Further objects and advantages of the invention will become apparent from the following description and claims, and from the accompanying drawings, wherein:

Figure 1 is a vertical cross sectional view taken through an improved polarized receptacle according to the present invention, shown with a polarized plug engaged therein.

Figure 2 is an enlarged longitudinal vertical cross sectional view taken through the plug employed in Figure 1.

Figure 3 is a transverse vertical cross sectional view taken on the line 3—3 of Figure 2.

Figure 4 is a top view of the main body portion of the plug of Figures 2 and 3, the outer cover thereof being removed.

Figure 5 is a transverse vertical cross sectional view taken on the line 5—5 of Figure 2.

Figure 6 is a horizontal cross sectional view taken on the line 6—6 of Figure 1.

Figure 7 is a horizontal cross sectional view taken on the line 7—7 of Figure 1.

Figure 8 is a cross sectional view taken on the line 8—8 of Figure 6.

Figure 9 is a cross sectional view taken on the line 9—9 of Figure 6.

Figure 10 is a fragmentary horizontal cross sectional view taken on the line 10—10 of Figure 2.

Figure 11 is a fragmentary vertical cross sectional view taken through the upper portion of a modified form of polarized plug receptacle according to the pres-

2

ent invention adapted for a three-wire circuit and shown with a three-contact plug engaged in the receptacle.

Figure 12 is a top plan view of the main body portion of the three-contact plug employed in Figure 11.

5 Figure 13 is a transverse vertical cross sectional view taken on the line 13—13 of Figure 12.

Referring to the drawings, and more particularly to Figures 1 to 10, 14 designates a conventional outlet box provided with a suitable receptacle-supporting strap 15 in which is secured a polarized plug receptacle according to the present invention, and designated generally at 16.

The receptacle 16 comprises a pair of opposed, hollow, mating, generally rectangular housing segments 17 and 18 of rigid insulating material, such as rigid plastic material, the hollow segments 17 and 18 being secured together in opposing relationship to define a rectangular housing by an internally threaded sleeve member 21 having head portions 22 and 22' at its opposite ends. The sleeve member 21 extends through a central aperture in the bight portion of the receptacle bracket member 15 and acts as a hollow rivet to fasten members 15, 17 and 18 together. A machine screw 19 extends through the center portion of a rectangular face plate 20 and is threadedly engaged in the internally threaded sleeve member 21.

The sleeve 21 passes through a central, generally rectangular spacing block 25 of rigid insulating material which fits snugly in the intermediate portion of the cavity defined between the opposing housing segments 17 and 18. Clamped between block 25 and the major wall of housing segment 17 is a rear contact plate 26, clearly shown in Figure 9, said contact plate being generally V-shaped and being formed at its opposite ends with apertures 27, 27 adapted to receive the ball end of a connecting plug, presently to be described. The end portions of the terminal plate 26 are formed with inwardly extending spring contact fingers 28 which are spaced around the apertures 27, as shown in Figures 1 and 9, said contact fingers 28 being adapted to receive the ball end 30 of a plug therebetween and to exert a locking action on said ball end to retain the plug in the receptacle, as will be presently explained.

The intermediate portion of the terminal plate 26 is formed with a terminal flange 31 exposed through a notch in the adjacent side wall of housing segment 17, as shown in Figure 6, said flange 31 being provided with terminal screws 33 which provide a means for electrically connecting terminal conductor 34 to the terminal plate 26.

Clamped between the block 25 and the inside surface of the major wall of housing segment 18 is a generally V-shaped terminal plate 35, said terminal plate being formed at its end portions with ring-like members 36, 36, defining apertures similar to the apertures 27, said ring-like members 36, 36 being formed with inwardly projecting, spaced spring contact fingers 37 adapted to conductively and grippingly engage with the conductive sleeve portion 56 of a plug 39 when the contact plug is inserted in the receptacle in the manner illustrated in Figure 1. The terminal plate member 35 is provided at its intermediate portion with a terminal flange 40 which is exposed through a notch in the side wall of housing segment 18, as shown in Figure 6, said flange 40 being provided with terminal screws 42. The terminal screws 42 are adapted to be connected to the grounded conductor 44 of a house wiring system.

As shown in Figures 8 and 9, the fastening sleeve 21 extends through the aligned contact plates 26 and 35, being located substantially midway between and in the same plane as the axes of the ring-like members at the ends of said plates.

As shown in Figure 1, the housing segment 18 is formed with conical, inwardly convergent apertures 45

aligned with the spaced apertured end portions of the respective terminal plates 26 and 35.

The plug 39, above mentioned, comprises a main body 46, of suitable insulating material, said main body having integrally moulded therein the shank member 47 whose outer end is formed with the ball contact element 30. A terminal screw 48 is engaged through the inner end of the shank 47 and is adapted to electrically connect a conductor 49 to said shank member 47, the conductor 49 forming part of an appliance cord 50, as shown in Figure 2.

The body 46 is formed with a reduced forward portion 51 and with a conical shoulder 54 adapted to fit the conical apertures 45 in the front wall of housing section 18. A groove 52 is formed between the forward end of the reduced portion 51 and the conical shoulder 54, and positioned in this groove is a contact sleeve member 56 having a stem portion 57 moulded in the body 54 and extending a substantial distance inwardly thereof. A terminal screw 58 extends through the inner end of the stem 57 and is threadedly engaged in the body 46, the shank 47 being bowed at its intermediate portion, as shown at 59 in Figure 10, to provide clearance between said shank portion and the terminal screw 58. The remaining conductor 60 of the line cord 50 is adapted to be connected to the terminal screw 58, and hence to the contact sleeve 56. As shown in Figure 4, the contact sleeve 56 is substantially flush with the forward portion 51 of main body 46, and is coaxially arranged with respect to the shank 47.

Designated at 62 is a cover member which is secured over the rear portion of the plug body 46, as by means of a fastening screw 63 which extends through and is suitably insulated from the rear end portion of shank 47 and which is threadedly engaged in the rear portion of body 46. The cover member 62 houses the terminal screws 48 and 58 and is preferably made of insulating material. Line cord 50 extends through an aperture 65 formed in the rear end wall of the generally cylindrical cover 62.

As shown in Figure 1, the plug 39 is easily inserted in the receptacle 16 through one of the conical apertures 45, the ball-shaped end 30 of the shank 47 being gripingly received between the spring-like contact fingers 28 and being locked thereby, whereas the sleeve element 56 is conductively engaged by the resilient fingers 37 of the grounded terminal plate 35. Thus, positive assurance is provided that the line conductor 60 of cord 50 will always be connected to the grounded conductor of the wiring system, so that the appliance, if it be of the polarized type wherein one conductor must be connected to the ground wire of the electric supply system, will always be connected to the supply circuit with the proper polarity.

In the form of the invention shown in Figures 11, 12 and 13, the receptacle, designated generally at 16', is provided with a third terminal plate 70 spaced between the inner terminal plate 26 and the outer terminal plate 35 by respective insulating spacer blocks 71 and 72 through which the main fastening sleeve 21 passes. The intermediate terminal plate 70 is provided with apertures around which are resilient contact fingers 74 adapted to engage a terminal sleeve 75 on a three-wire plug 76, the terminal sleeve 75 being spaced between and insulated from the ball end 30' of the shank of the plug and the ground sleeve 56' of the plug.

As shown in Figure 13, the ground sleeve 56' is formed with a contact arm 77 which is moulded in and extends longitudinally of the main body of the plug, shown at 78, the arm 77 being threadedly engaged by a terminal screw 79, shown in Figure 12. The contact sleeve 75 is similarly formed with an arm 80 which is embedded in and extends longitudinally of the body 78, a terminal screw 81 being threadedly engaged in the inner end of the arm 80. A third terminal screw 82 is threadedly en-

gaged in the inner end of the shank element of the plug, designated at 83. The respective wires of a conventional three-wire line cord may be clampingly secured by the terminal screws 79, 81 and 82, and may be thus electrically connected respectively to sleeve member 75, sleeve member 56', and shank member 83 in the manner illustrated in Figure 12.

A generally cylindrical cover 62' receives the rear end portion of the plug body 78 and is detachably secured thereto by a fastening screw 63 in the same manner as previously described in connection with the two-wire plug 39.

The polarized outlets and plugs above described are especially useful with power tools and other electrical appliances requiring a special or second ground wire to provide safety against shock.

By the use of the present invention, the second ground or safety wire is eliminated, since the safety wire may be connected to the body of the tool or appliance itself, and the polarized plug insures proper grounding of said body. This safety feature may be employed with all appliances.

In wiring installations where Romex cable is used, the outlet boxes are not grounded (unless special grounded Romex cable is used) thereby making the safety ground wire of the power tool or appliance useless. By employing polarized outlets and plugs, according to this invention, in such installations, maximum protection against shock is provided at all times, using one line wire and one ground wire.

While certain specific embodiments of an improved polarized receptacle and plug have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A plug receptacle for use with a plug of the type comprising a contact shank having a contact ball at its end and a contact sleeve surrounding said shank and insulated therefrom comprising a housing having parallel front and rear walls and opposite side walls, a first substantially V-shaped terminal plate secured to the inside surface of said front wall, a second substantially V-shaped terminal plate secured to the inside surface of said rear wall opposite said first V-shaped plate and parallel thereto, said front wall being formed with apertures to receive said plug, said terminal plates being formed with ring-like members at their ends defining apertures aligned with said first-named apertures, a transverse fastener extending through said front and rear walls and between the side arms of said V-shaped terminal plates in substantially the same plane as the axes of said apertures, spring contact fingers on the first terminal plate extending inwardly and rearwardly from the apertures therein and being engageable with the contact sleeve of the plug, and spring contact fingers on the second terminal plate extending inwardly and forwardly from the apertures therein and being engageable with the contact ball of the plug.

2. A plug receptacle for use with a plug of the type comprising a contact shank having a contact ball at its end and a contact sleeve surrounding said shank and insulated therefrom comprising a housing having parallel front and rear walls and opposite side walls, a first substantially V-shaped terminal plate secured to the inside surface of said front wall, a second substantially V-shaped terminal plate secured to the inside surface of said rear wall opposite said first V-shaped plate and parallel thereto, said front wall being formed with apertures to receive said plug, said terminal plates being formed with ring-like members at their ends defining apertures aligned with said first-named apertures, a transverse fastener extending through said front and rear walls and between the side arms of said V-shaped terminal plates in substantially

the same plane as the axes of said apertures, spring contact fingers on the terminal plate spaced around the apertures therein and extending inwardly and rearwardly, said contact fingers being engageable with the contact sleeve of the plug, and spring contact fingers on the second terminal plate extending inwardly and forwardly from the apertures therein, said last-named contact fingers being spaced around the apertures in the second terminal plate and being formed and arranged to receive and lockingly engage with the contact ball of the plug.

3. A plug receptacle for use with a plug of the type comprising a contact shank having a contact ball at its end and a contact sleeve surrounding said shank and insulated therefrom comprising a housing having parallel front and rear walls and opposite side walls, a first substantially V-shaped terminal plate secured to the inside surface of said front wall, a second substantially V-shaped terminal plate secured to the inside surface of said rear wall opposite said first V-shaped plate and parallel thereto, said front wall being formed with apertures to receive said plug, said terminal plates being formed with ring-like members at their ends defining apertures aligned with said first-named apertures, a transverse fastener extending

through said front and rear walls and between the side arms of said V-shaped terminal plate in substantially the same plane as the axes of said apertures, spring contact fingers on the first terminal plate spaced around the apertures therein and extending inwardly and rearwardly, said contact fingers being engageable with the contact sleeve of the plug, spring contact fingers on the second terminal plate extending inwardly and forwardly from the apertures therein, said last-named contact fingers being spaced around the apertures in the second terminal plate and being formed and arranged to receive and lockingly engage with the contact ball of the plug, respective terminal lugs on said terminal plates extending through opposite side walls of the housing, and respective terminal

15 screws in said side walls and extending through said terminal lugs.
